UNITED STATES PATENT OFFICE.

FRANK H. STEWART, OF ELKINS PARK, PENNSYLVANIA.

WOVEN WEB AND PRODUCTION OF THE SAME.

1,324,627.

Specification of Letters Patent.

Patented Dec. 9, 1919.

Application filed April 14, 1919. Serial No. 289,841.

To all whom it may concern:

Be it known that I, FRANK H. STEWART, a citizen of the United States, residing in Elkins Park, Montgomery county, Pennsylvania, have invented certain Improvements in Woven Webs and Production of the Same, of which the following is a specification.

My invention relates to that type of narrow ware fabrics such as tape, belting, ribbon, or the like (hereinafter, for convenience, and to avoid repetition being characterized simply as "web") in which the weft thread is carried to and fro through one and the same shed of warp threads and, at one selvage of the web forms loops extending beyond the warp thread at that edge, the objects of my invention being to prevent the drawing of these loops into the shed of warp threads on the return run of the weft thread, and also to prevent raveling of the edge warp thread, the latter not being confined by the loops.

In the accompanying drawing,

Figure 1 is a face view, on an exaggerated scale, of a piece of web woven in accordance with my invention;

Fig. 2 is a sectional view on the line 2—2, Fig. 1;

Fig. 3 is a view similar to Fig. 2 but illustrating web embodying a modified form of my invention, and

Fig. 4 is a view of certain mechanism used in weaving web such as shown in Figs. 1 to 3.

Referring to the web shown in Figs. 1 and 2 of the drawing, 1—1 represent a set of warp threads and 3 a weft thread interwoven therewith, the warp threads 1 being shedded between successive to and fro runs

3^a and 3^b of the weft thread 3, so that double runs of the same lie in each shed of the warp threads and form loops 4 at one selvage of the web.

With the loops 4 are intertwined a pair 45 of selvage threads 5 and 5^a, these selvage threads being given a half twist in respect to each other between each of the successive runs 3^b and 3^a of the weft thread so that the selvage threads embrace each loop 4 and are 50 twisted in respect to each other between successive loops. The selvage threads, thus intertwined, serve to grip the loops 4 and prevent them being drawn into the sheds of the warp threads 1 and also retain the edge 55 warp thread in place and prevent it being raveled out.

In the form of web shown in Fig. 3 of the drawing, the selvage threads 5 and 5^a are given a full twist in respect to each other between successive loops, thus causing them to 60 interlock with each other and exert a tighter grip upon the loops than is the case with web as shown in Figs. 1 and 2.

The selvage threads may be disposed at the left hand selvage of the web, at the right hand selvage of the same, or in case two weft threads are employed, at both selvages.

Although the selvage threads may be supplied and twisted by any suitable means, I prefer to make use of mechanism such as shown in Fig. 4 of the drawing. The threads 5 and 5^a are fed to the web parallel with the edge warp thread and are supplied from spools 6 and 6^a mounted upon a disk 7 secured to a shaft 8, and are guided by eyes 9 and 9^a formed in the disk 7. Between each of the successive runs 3^b and 3^a of the weft thread 3, a movement of either half or full rotation is imparted to the shaft 8, thereby 80 correspondingly rotating the thread carrying and guiding disk 7 and twisting the threads 5 and 5^a in respect to each other and causing them to embrace and grip the last formed loop 4. 85

I claim:

1. A woven web comprising a set of warp threads, a pair of selvage threads disposed at one side of the warp threads, and a weft thread passing to and fro through each shed of warp threads and forming loops at the edge of the web, said pair of selvage threads embracing each loop and being twisted in respect to each other between successive loops. 90

2. A woven web comprising a set of warp threads, a pair of selvage threads disposed at one side of the warp threads, and a weft thread passing to and fro through each shed of warp threads and forming loops at the edge of the web, said selvage threads being disposed one above and the other below said loops throughout the web and being interlocked with each other between successive loops. 100

3. The mode herein described of weaving a web, said mode consisting in passing a weft thread to and fro through each of a number of successive sheds of warp threads and between a pair of selvage threads, thereby forming loops in said weft thread at the edge of the web and between the sel- 110

vage threads, and twisting said selvage threads in respect to one another between successive loops.

4. The mode herein described of weaving a web, said mode consisting in passing a weft thread to and fro through each of a number of successive sheds of warp threads and between a pair of selvage threads,

thereby forming loops in said weft thread at the edge of the web and between the selvage threads, and interlocking said selvage threads with each other between successive loops.

In testimony whereof I have signed my name to this specification.

FRANK H. STEWART.
